UNITED STATES PATENT OFFICE.

GEORGE G. McCAMANT, OF MATTOON, ILLINOIS.

STARCHING MACHINE.

Application filed May 23, 1921. Serial No. 471,705.

To all whom it may concern:

Be it known that I, GEORGE G. McCAMANT, a citizen of the United States, residing at Mattoon, in the county of Coles and State 5 of Illinois, have invented certain new and useful Improvements in Starching Machines, of which the following is a specification.

This invention has for its object the provision of simple and inexpensive means whereby starch may be readily applied to collars or to neckbands of shirts or to other articles of wearing apparel to which it may be desired to impart a stiffened finish. The 10 invention also seeks to provide a device which may be readily set up at any desired point for use and which, when not in use, may be easily removed and stored out of the way, and a further object of the invention 15 is to so arrange the working parts that the starch will not be spattered upon the operator nor applied to those parts of the garment or other article which are to remain in a soft condition. The several stated objects and other incidental objects which will appear in the course of the following description are attained in such an apparatus as is illustrated in the accompanying drawings and the invention resides in certain 20 novel features which will be particularly pointed out in the appended claims.

In the drawings—

Figure 1 is a perspective view, with parts broken away, showing my improved apparatus arranged for use;

Fig. 2 is an enlarged sectional elevation of the starch box and the starch rolls with the parts immediately adjacent the same.

In carrying out my invention, I employ 40 a base plate 1 which may be of any desired material and is adapted to be secured to a table 2 or other support by clamps 3 in an obvious manner. Between the ends of the base plate 1, a standard 4 rises therefrom 45 and to the upper end of this standard, I secure an arm 5 which is adapted to project forwardly therefrom and has a conical or tapered roller 6 loosely mounted upon its forward end. Below its upper extremity, 50 the standard 4 is constructed with an opening or slot 7 and in the said opening, I pivotally secure an arm 8 which is adapted to project forwardly from the standard and is equipped at its forward end with a loosely 55 mounted tapered or conical roller 9 which is covered with some textile or other soft

absorbent material. To the arm 8 in front of the standard, I pivotally attach the upper end of a link 10 which, as shown clearly in Fig. 1, consists of two members provided 60 with longitudinal slots 11 and connected by a set bolt 12 inserted through the slots in an obvious manner. The lower end of the link is pivoted to a foot lever or pedal 13 which is fulcrumed upon a base plate 14 of 65 sufficient area to set firmly upon the floor of the room in which the apparatus is used. Below the lower arm 8, I secure to the standard 4 a shelf or rest 15 upon which the starch box 16 is to be supported and the 70 starch box may be of any desired dimensions or material but will preferably be of metal in order that the heat of the starch may be retained for as long a period as possible. The back wall 17 of the starch 75 box terminates below the sides of the same, as clearly shown, so that ample play of the pivoted arm 8 will be permitted. To retain the starch box in position upon the shelf while the apparatus is in use, I provide the 80 wings or side plates 18 which are hinged to the side edges of the shelf and are adapted to be swung up close against the sides of the starch box, as will be readily understood on reference to Fig. 1. One of these wings 85 or side plates carries a pivotally mounted hook 19 adapted to engage an eye 20 on the other wing so that when the wings are swung up against the starch box and the hook engaged in the eye, the hook will extend across the front end of the box and prevent the same sliding forward from the shelf or rest. I also provide hooks 21 upon the wings near the rear ends thereof adapted to engage eyes 22 upon the standard so 90 that the wings will be positively held in their raised position.

A brace 23 is secured to the standard 4 and depends therefrom behind the link 10, and is equipped at its lower end with guides 100 24 between which the link plays. The brace may conveniently be a flat plate and may be provided with a central groove to receive the link whereby to prevent movement of the link and hold it to a rectilinear path. 105

In using the apparatus, the weight of the lower roller 9 and the arm 8 with the link 10 pivoted to said arm will serve to hold the said roller in its lowered position, as shown in full lines in Fig. 1 and in dotted lines in 110 Fig. 2. The covering of the roller 9 will be thereby caused to dip into the starch within

the box 16 and become coated therewith. The collar or other article to which starch is to be applied is brought into position below the upper roller 6 and the pedal 13 is then rocked so as to lift the link 10 and thereby swing the arm 8 upwardly so that the roller 9 will be brought to the roller 6 and against the end of the article which has been placed in position beneath said roller. The article is then drawn between the rollers from end to end and, as the roller 9 is held in its raised position and in contact with the article by pressure upon the pedal 13, sufficient frictional engagement will be created between the article and the rollers to effect rotation of the rollers and, consequently, the coated surface of the lower roller will move with the article and cause starch to be applied to the same.

20 After one surface of the article has been thus coated, the article may be reversed and drawn back between the rollers end for end so that it will become impregnated with the starch rapidly and without fatiguing the operator. After one article has been thus starched, the pressure upon the pedal is removed whereupon the roller will again drop into the starch box and absorb another film of the starch. The side edges of the starch box and of the wings 18 will serve as guides for the operator in moving the article between the rollers and will thereby guard against dropping of the article or pinching of the operator's hand between the rollers.

30 In starching the neckband of a shirt or any part of an article the main portion of which is to be kept soft, the front wall of the starch box will serve as a support to prevent the body of the garment passing between the rollers so that the starching operation may be performed expeditiously and without waste of starch and without causing an application of starch to those parts which it is desired to keep soft. When the supply of starch has become exhausted or has cooled to such an extent as to be no longer easily workable, the starch box may be removed and another heated box substituted therefor in an obvious manner without any appreciable loss of time.

40 It will be readily noted that I have provided an exceedingly simple portable hand-operated apparatus which may be readily set up at any convenient point when its use is desired and as readily set aside when it is no longer to be used. By the use of my apparatus, the starch is economically but efficiently supplied to the goods and the operation may be performed very rapidly.

50 The extensible construction of the pitman 10 permits the same to be readily adjusted to the height of the table or other support

upon which the device is to be placed and also to the height of the operator. Both the rollers are loose upon their respective supports and, consequently, rotate only when an article is drawn between them, and by reason of their frictional engagement with the article. Liability of the operator's hand being caught and drawn into the bight between the rolls is, therefore, minimized and the starch is more effectively applied to the article inasmuch as the rotation of the rollers is controlled by the movement of the article, and this movement will be obviously regulated so that the starch will be uniformly applied to the entire surface and will impregnate the fabric evenly throughout the same.

Having thus described the invention, what is claimed as new is:

1. An apparatus for the purpose set forth comprising a base plate, a standard rising therefrom, means for securing the base plate upon a fixed support, a starch box mounted upon the standard, an arm projecting from the standard, a swinging arm mounted upon the standard below the first arm, mating rollers carried by said arms, the lower roller being adapted to absorb starch from the starch box, a link pivoted to and depending from the swinging arm in advance of the standard, and means for actuating said link.

2. An apparatus for the purpose set forth comprising a base plate, a standard rising therefrom, means for securing the base plate upon a fixed support, a starch box mounted upon the standard, an arm projecting downwardly from the standard, a swinging arm mounted upon the standard below the first arm, mating reversely tapered rollers loosely mounted on the said arms, the lower roller being adapted to absorb starch from the starch box, and means for actuating said swinging arm.

3. A starching apparatus comprising a standard, a shelf projecting from the standard, a starch box carried by said shelf, side plates hinged to the shelf and adapted to be swung upwardly against the sides of the starch box, fastening devices to extend across the front of the starch box and connect the said side plates, an arm projecting from the standard above the starch box, a swinging arm mounted on the standard between the starch box and the first arm, rollers carried by the said arms, and means for swinging the lower arm whereby to cause the roller thereon to dip into the starch in the starch box or to assume an operative position co-operating with the roller on the upper arm.

In testimony whereof I affix my signature.

GEORGE G. McCAMANT. [L.S.]
